UNITED STATES PATENT OFFICE

116,546

DESIGN FOR A SOAP CAKE

Leland J. Arms, San Francisco, Calif.

Application April 10, 1939, Serial No. 84,187

Term of patent 14 years

To all whom it may concern:

Be it known that I, Leland J. Arms, a citizen of the United States, residing in the city and county of San Francisco, State of California, have invented a new, original, and ornamental Design for a Soap Cake, of which the following is a specification, reference being had to the accompanying drawing, forming part thereof.

The figure is a perspective view of a soap cake, showing my new design.

I claim:

The ornamental design for a soap cake, as shown.

LELAND J. ARMS.
